UNITED STATES PATENT OFFICE.

JOSEPH L. DOSTAL, OF DETROIT, MICHIGAN, ASSIGNOR TO EARL HOLLEY, OF DETROIT, MICHIGAN.

COOLING MEANS FOR PERMANENT MOLDS.

Application filed July 9, 1927. Serial No. 204,572.

The object of this invention is to improve the cooling of a series of molds, such as those illustrated in my Patent #1495728, and is an improvement on the cooling means shown in Patent #1593294.

The specific object of the invention is to economize the quantity of air used, as in the construction shown in Patent #1593294 more than one-half of the air is wasted.

10 An additional object is to decrease the liability of the rotating mechanism to clog up with dust and dirt, by utilizing the pressure of the cooling air to automatically keep the mechanism clean.

15 Figure 1 shows a cross sectional elevation on plane 1-1 of Figure 2.

Figure 2 shows a plan view.

In the figures, A is a stationary base located on supports B (only one shown), upon 20 which is mounted a shaft C about which rotates a table D. A roller bearing E is provided to support D on A, so as to reduce friction. The hollow space between A and D is used as an air receiver for the cooling air 25 received from a pipe F. The air from the space A D is distributed through the pipes G, each of which supplies the air for cooling a pair of molds through the cooling nozzles H J. The molds are mounted on extension bars K, carried around by the table D, and on the supports L M, as shown in the patent to Dostal and Anderson, #1570950. The molds are shown in broken 30 lines, but of course they may be of any shape and size.

Operation—The cooling air entering at F is economically directed against the molds through the nozzles H J, so as to most ef-

fectively cool the molds. The tendency of air to leak out through the bearing E positively prevents the entry of dust and dirt into the bearings, so that the life of the roller bearing E and its track is more than doubled.

Finally, the temperature of the bearing E is kept sufficiently low so that the lubricant will neither be evaporated and cake, nor will it become so fluid as to escape.

What I claim is:—

1. In combination with a traveling series 50 of molds, located on a rotating table, a stationary base located below and supporting said table, and forming an enclosed space therewith, a stationary pipe delivering air to said space, air cooling nozzles mounted on 55 said table, said cooling nozzles being adapted to cool said molds.

2. In combination with a traveling series 60 of molds, located on a rotating table, a stationary base located below and supporting said table, and forming an enclosed space therewith, an annular bearing on said base supporting said table, a stationary pipe delivering air to said space, air cooling nozzles 65 mounted on said table, said cooling nozzles being adapted to cool said molds.

3. In combination with a traveling series 70 of molds located on a rotating table, cooling means comprising an enclosed space located in the upper central portion of said table, a stationary pipe delivering air to said space, air cooling nozzles mounted on said table, a plurality of pipes connecting said air nozzles to said enclosed space.

In testimony whereof I affix my signature.

JOSEPH L. DOSTAL.
